US00D980829S

(12) **United States Design Patent** (10) **Patent No.:** **US D980,829 S**
Chen (45) **Date of Patent:** **** Mar. 14, 2023**

(54) **MICROPHONE**

(71) Applicants: **Guangzhou Rantion Technology Co., Ltd.**, Guangzhou (CN); **Donner Technology LLC**, Charlotte, NC (US)

(72) Inventor: **Sheng Chen**, Guangzhou (CN)

(73) Assignees: **GUANGZHOU RANTION TECHNOLOGY CO., LTD.**, Guangzhou (CN); **DONNER TECHNOLOGY LLC**, Charlotte, NC (US)

(**) Term: **15 Years**

(21) Appl. No.: **29/802,592**

(22) Filed: **Aug. 6, 2021**

(51) LOC (14) Cl. **14-01**

(52) U.S. Cl.

USPC **D14/228**

(58) **Field of Classification Search**

(57) **CLAIM**

An ornamental design for a microphone, as shown and described.

DESCRIPTION

FIG. 1 is a perspective view of a microphone showing my new design;

FIG. 2 is a front view of the microphone of FIG. 1 thereof; FIG. 3 is a rear view of the microphone of FIG. 1 thereof; FIG. 4 is a left side view of the microphone of FIG. 1 thereof;

FIG. 5 is a right side view of the microphone of FIG. 1 thereof;

FIG. 6 is a top view of the microphone of FIG. 1 thereof; and,

FIG. 7 is a bottom view of the microphone of FIG. 1 thereof. The broken lines depict portions of the microphone that form no part of the claimed design.

1 Claim, 3 Drawing Sheets
